United States Patent Office

Des. 191,362
Patented Sept. 19, 1961

191,362

GLIDER SWING

Taylor W. Jackson, Denver, Colo., assignor to
Marjorie Jackson, Denver, Colo.

Filed Apr. 14, 1961, Ser. No. 64,737

Term of patent 14 years

(Cl. D34—5)

Fig. 1

Fig. 2

Fig. 3.

FIG. 1 is a perspective view of a glider swing showing my new design;

FIG. 2 is a top plan view thereof; and

FIG. 3 is an end elevational view thereof.

I claim:

The ornamental design for a glider swing, as shown.
